(57) **CLAIM**

The ornamental design for the arc lighter as shown and described herein.

DESCRIPTION

FIG. 1 is an elevated, perspective view of the arc lighter in accordance with my invention;

FIG. 2 is a front view thereof;

FIG. 3 is a back view thereof;

FIG. 4 is a side view of my invention as shown in FIG. 1, FIG. 5 is an opposing side view being the mirror image thereof; and

FIG. 6 is a top view thereof;

FIG. 7 is a bottom view thereof; and,

FIG. 8 is an opposite perspective view of the arc lighter in FIG. 1.

The broken lines shown in FIGS. 1-8 are for illustrative purposes only and form no part of the claimed design.
